Alfons Bach, New York, N. Y.

Application March 11, 1938, Serial No. 75,759

Term of patent 7 years

To all whom it may concern:

Be it known, that I, Alfons Bach, a citizen of the United States, and a resident of New York city, in the county and State of New York, have invented a new, original, and ornamental Design for a Cabinet or Similar Article, of which the following is a specification.

Reference is had to the accompanying drawing, forming part thereof.

In the drawing:

Fig. 1 is a perspective view of the cabinet, showing my new design;

Fig. 2 is a front elevational view thereof, on a reduced scale; and

Fig. 3 is a top plan view on a reduced scale.

The characteristic feature of the design resides in the combination of the corners of the cabinet shaped in a 45 degree angle and the concave curvature of the front of the cabinet, as shown.

I claim:

The ornamental design for a cabinet or similar article as shown and described.

ALFONS BACH.
